UNITED STATES PATENT OFFICE.

FORREST WILLIAM MANKER, OF JACKSON HEIGHTS, NEW YORK, ASSIGNOR TO SURFACE COMBUSTION COMPANY, OF NEW YORK, N. Y., A CORPORATION OF NEW YORK.

CONTINUOUS SLAB-HEATING FURNACE.

Application filed July 15, 1925. Serial No. 43,699.

This invention relates to furnaces and more particularly to furnaces for continuously heating slabs or pairs or the like.

It is an object of the invention to provide 5 a slab heating furnace in which the slabs or other work to be heated may be efficiently and uniformly heated from below as well as above while they are being moved through the heating chamber.

10 Another object is to provide a slab heating furnace in which the tracks on which the slabs are supported shall be elevated from the floor of the heating chamber whereby to form channels or conduits along which 15 the hot gases may flow beneath slabs to heat the same.

A still further object is to provide a slab heating furnace having longitudinally extending channels along which the hot gases 20 may flow and to provide means for covering over certain portions of the side channels, more particularly in front of the side doors through which the slabs may be removed from the furnace, and to provide means for 25 intercepting the flow of gases in the side channels before they enter the covered over channels.

An additional object is to provide a slab heating furnace in which the slab supporting 30 tracks shall have a gradient extending upwardly from the charging to the discharging end of the heating chamber whereby to keep the slabs from falling over on their sides toward the discharging end of the chamber as 35 they are moved therethrough.

Another object is to provide a slab heating furnace of such construction that the burning gases shall pass through the heating chamber continuously in one direction and 40 out of the same through the ports in the floor of the chamber beyond the last side door so that any air entering the heating chamber by way of the doors may be prevented from exercising any pronounced oxidizing effect on the slabs while they are being 45 heated.

A still further object is to provide a slab heating furnace wherein the flow of gases from the heating chamber may be regulated 50 and wherein the air which supports secondary combustion of the combustible gases may be readily regulated.

Another object is to provide a furnace construction wherein a recuperator for pre-heating the air to be used for supporting

secondary combustion shall be located below the heating chamber in such manner that the products of combustion may pass directly from said chamber through the recuperator and to provide a collecting chamber for the heated air between the floor of the heating chamber and the top of the recuperator.

The above and other objects of the invention, with their attendant advantages will more fully appear from the detailed description taken in connection with the accompanying drawings which form a part of this specification.

Referring to the drawings:

Figure 1 is a longitudinal, vertical section 79 through the improved slab heating furnace, parts being broken away to more clearly illustrate the construction;

Fig. 2 is a vertical cross-section taken on line 2—2 of Fig. 1 and illustrating the relation of the combustion chamber to the heating chamber and to the air and gas passages and also showing certain features of construction within the heating chamber;

Fig. 3 is a vertical cross-section taken on line 3—3 of Fig. 1 and illustrating the construction of the recuperator and certain features of construction within the heating chamber; and

Fig. 4 is a horizontal cross-section taken 85 on line 4—4 of Fig. 1 parts being broken away to more clearly show certain features of construction.

In the drawings, 10 indicates the gas producers of which two are shown arranged side 90 by side along one side of a slab heating chamber 11 into which they discharge their gases by way of ports or passages 12 and combustion chamber 14 opening into the slab heating chamber.

The air for supporting secondary combustion of the producer gases enters the combustion chamber through upright ports 16 in the partition wall or baffle 18 which is in effect a part of the side wall of the heating chamber. These ports are in communication with an air chamber 20 formed at the top of a recuperator 22, suitable passages 23 connecting the air chamber with said ports. Fresh air is admitted to the recuperator through suitable passages 24 extending therebeneath and is heated to a high temperature as it circulates through the recuperator, which latter is heated by the products of combustion flowing from the slab heating

chamber as will presently be explained. The recuperator is preferably of tile construction as illustrated in Figs. 1 and 3 and the air is heated by passing around the tiles in grooves or channels 25 provided therebetween, the heated air collecting in the air chamber 20.

The partition or baffle wall 18 is preferably provided with a transversely extending passage 25 which is in effect a distributing 10 manifold for the air coming from the hot-air collecting chamber 20.

The burning gases from the combustion chamber after traveling the length of the heating chamber, pass out of the same by 15 way of outlet ports 26 in the floor thereof, the ports being located at the far end of the chamber (Figs. 1 and 4). These ports open on an upright passage 28 (Fig. 4) which extends in front of the recuperator. The products of combustion after passing through the recuperator enter a passage 29 at the far end thereof from whence they pass by suitable passage 40 (Fig. 1) to the stack, not shown.

25 The effective size of the outlet ports 26 may be regulated by tiles 30 which rest on the floor of the heating chamber and which are adapted to be moved over the ports by a suitable tool inserted through the inspection 30 ports 31 extending through the end wall of the furnace. By varying the size of the outlet ports 26 the rate of flow of the burning gases through the heating chamber may be readily regulated and the circulation of 35 the same around the work effectually controlled.

The effective size of the air ports 16 may also be varied by shifting the tiles 33 resting on top of the partition or baffle 18, access being had to the tiles through inspection 40 ports 32 in the adjacent side wall of the furnace. By thus regulating the amount of air which is to be mixed with the combustible gases coming from the producer, the character and temperature of the flame may be 45 readily controlled. In other words, the flame can be readily controlled so as to be a reducing flame or oxidizing flame at will. Ordinarily the admission of air would be 50 such that a reducing flame is obtained in order to prevent the formation of scale on the slabs or other work being heated.

The slabs to be heated are generally indicated at X and are adapted to be supported on a pair of tracks 38 which rests on piers 36 mounted in the central portion of the heating chamber in spaced relation to each other and spaced from the side walls of the heating chamber, thus forming a central and side channels in which the burning 60 gases may flow toward the far end of the furnace as will presently appear. The slabs slide on the tracks 38 as they are moved through the heating chamber from one end 65 to the other thereof, the slabs being fed to

said chamber by any suitable charging device in a position somewhat inclined from the vertical. They are prevented from falling over on their sides towards the charging end by any suitable means such as dogs 40 which engage with the last slab that has been entered into the furnace.

In accordance with the present invention the slab supporting piers gradually increase in height from the charging to the discharging end of the heating chamber whereby a gradient is produced. By providing a gradient the slabs are more readily maintained in a sloping position or at an angle to the vertical and consequently there is less tendency for them to fall over forwardly on their sides as they are pushed through the chamber.

The burning gases coming from the combustion chamber pass down the length 85 of the heating chamber, being drawn toward the far end thereof by the draft at the outlet ports 26. Some of the burning gases find their way into the central and side channels 54 and 56 respectively formed 90 by the piers 36, and flow toward the far end of the heating chamber. The burning gases will also circulate between the slabs inasmuch as there will usually be some space between them due either to burs or projections in their faces or because they are loosely stacked. It will, therefore, be appreciated that the burning gases circulate not only over the slabs but also below and between them with the result that they are 100 uniformly heated throughout. The piers are provided opposite the combustion chamber with lateral ports 52 through which the hot gases may circulate from one channel to another and more particularly from side 105 channels 56 into the central channel 54 for reasons that will presently appear.

Extending along one side of the heating chamber are a plurality of doors 58 through which the heated slabs may be taken out of the furnace the doors being arranged on a level with the tracks 38 on the tops of the slab supporting piers. Arranged in each of the side channels is a transversely extending wall 60 which forms a barrier to the 110 free flow of gases in the side channels. Each side channel is covered over by a slab 62 which extends from the barrier 60 a short distance beyond the last of the side doors. The covering slab may be one continuous 115 piece or a plurality of pieces as indicated in the drawings. While the barrier 60 intercepts the free flow of gases in the side channels, means are, however, provided whereby the hot gases from the central channel may flow into the closed over channels through lateral ports 64 provided in the piers beyond the barrier.

By covering over the side channel in front of the side doors 58, the flames from the 120

burning gases are prevented from passing through the doors when the latter are opened for the removal of the slabs. In addition to the side doors 58 there is provided an end door 66 through which the slabs may be removed if desired.

Inasmuch as the slabs to be heated are supported on elevated tracks rising from the floor of the heating chamber, some of the flames or burning gases which enter the heating chamber from the side thereof will first be deflected downwardly by the curved roof of the heating chamber into that side channel farthest removed from the baffle 18 and under the slabs resting on the tracks or piers, the lateral passages or ports 52 in the piers, however, permitting the flames or hot gases to circulate freely beneath the slabs. The draft created by the stack makes itself felt at the ports 26 in the far end of the heating chamber and consequently the hot gases will travel along the channels toward these ports and out through the same. By reason of the fact that barriers 60 are provided in side channels, an eddying effect is set up in the side channels opposite the combustion chamber with the result that the ends of the slabs projecting over the side channels will become thoroughly heated by the time they have reached the side doors 58. Furthermore, inasmuch as the hot gases in the central channel are permitted to flow into the covered-over portions of the side channels, the cover tiles 62 or slabs are thoroughly heated from below and thus, while they prevent the hot gases in the side channel from flowing through the doors when the latter open, they assist in keeping the ends of the slabs hot by radiation of their heat.

While both side channels opposite the side doors have been shown as covered over with tiles, it is within the spirit of the invention to dispense with that cover tile and barrier farthest removed from the side doors 58, for the obvious reason that only one side of the heating chamber is provided with side doors through which it is desired to prevent the flow of hot gases.

It will be noted that the hot gases flow continuously toward the far end of the heating chamber. By thus confining the burning gases to a one direction movement before passing out of the heating chamber, any air which may leak in through the doors 58 is carried away from the work toward the outlet ports 26 without having had an opportunity of passing to the front of the chamber and without having sufficient time to exercise any material oxidizing effect on the heated slabs.

Furthermore, by providing for the control of the heated air which enters the combustion chamber, the flames may be readily maintained as a reducing flame so that any

air which enters through the side doors 58 or through the end door 66 will combine with the burning gases rather than exercising an oxidizing effect on the slabs.

The recuperator is located below the floor of the heating chamber to provide as direct a passage as possible for hot products of combustion as they pass on their way to the stack. Furthermore, this construction enables a hot-air collecting chamber to be provided directly below the heated floor of the heating chamber whereby the air will be further heated before passing on its way to the combustion chamber.

What is claimed is:

1. In a continuous heating furnace opening into one side of the heating chamber, the combination of elevated work-supporting piers extending longitudinally of the heating chamber in spaced relation to each other and the chamber side walls to form open-top channels across which the work to be heated is disposed for heating from below and above, means establishing transverse communication between the channels for a limited portion of their length, and means for delivering a stream of hot gases from an opening in the chamber side wall in a direction above and across the communication portion of said channels in a manner to permit said gases to flow downwardly along the chamber wall opposite said openings and transversely through the communicating portions of said channels.

2. In a continuous heating furnace having its combustion chamber at one side of the heating chamber and having doors along a side wall thereof, the combination of elevated piers extending longitudinally of the heating chamber in spaced relation to each other and to the side walls of the same to form channels and on which piers the work to be heated supported and moved from one end of the heating chamber to the other, passages in the piers through which the hot gases may pass from channel to channel whereby to heat the under part of said work, means for drawing off the products of combustion at the far end of the heating chamber, and means covering over the side channel adjacent the side doors to prevent the upward flow of gases from said channel.

3. In a furnace for heating slabs and the like, the combination of means for entering burning gases into the heating chamber from a side thereof, a pair of tracks raised above the floor of the heating chamber and extending lengthwise thereof in spaced relation to each other and to the sides of the heating chamber whereby open-top central and side channels are formed, means covering over the side channels from a point intermediate the length of the heating chamber and one end thereof, doors opening into the heating chamber above and alongside a

covered-over channel, and ports in the floor of the heating chamber beyond the last side door thereof and through which ports the products of combustion may pass out of the chamber, the burning gases upon entering the chamber passing over the work resting on the tracks and under the same by way of the said channels, the covered-over channel in front of the said doors preventing the hot gases from passing out through the doors from below the work when the doors are opened.

4. In a continuous heating furnace having a combustion chamber at one side of the heating chamber, the combination of two elevated piers extending longitudinally of the heating chamber in spaced relation to each other and to the side walls of the same to form channels and on which piers the work to be heated is supported and moved from one end of the heating chamber to the other, the hot gases from the combustion chamber passing over and under the ends of the work into the side channels, transversely extending passages in the piers through which the hot gases pass from the side channels into the central channel, discharge ports in the floor of the heating chamber at the far end thereof through which the products of combustion may pass out of the chamber, and means for regulating the effective size of the discharge ports.

5. In a continuous heating furnace having a combustion chamber at one side of the heating chamber and having doors along a side wall of the latter, the combination of two elevated piers extending longitudinally of the heating chamber in spaced relation to each other and to the side walls of the same to form open-top channel and on which piers the work to be heated is supported and progressed from one end of the heating chamber to the other, the hot gases from the combustion chamber passing over and under the ends of the work into the side channels, lateral ports in the piers through which the burning gases coming from the combustion chamber may pass from channel to channel whereby to heat the under-side of said work, discharge ports in the floor of the heating chamber and at the far end thereof for drawing off the products of combustion, and means intercepting the flow of burning gases in the side channel in front of said doors.

6. The combination specified in claim 2, and means in front of the first side door and the adjacent side channel intercepting the free flow of hot gases in said channel, the adjacent pier having a passage through which hot gases may flow to the closed-over portion of the side channel.

7. In a pair or slab heating furnace, the combination of a heating chamber, means for admitting air and combustible gas to the

chamber at one side thereof adjacent the charging end of the same, a pair of slab-supporting piers extending longitudinally of the chamber in spaced relation to each other and to the side walls of the chamber whereby side and central channels for the flow of hot gases are formed, a stop wall in each of the side channels intermediate the ends thereof, means covering over the side channels from the stop walls rearwardly whereby closed-over conduits are formed, ports extending through the piers on either side of the stop walls whereby in front of said walls the hot gases may flow from the side channels into the central channel and on the other side of said walls from the central channel into the closed-over conduits, side doors in one side wall of the heating chamber along and above the adjacent closed-over conduit, ports in the floor of the heating chamber at the rear ends of the channels through which the products of combustion may pass out of the heating chamber, means for controlling the flow of the products of combustion from the heating chamber, and means for controlling the amount of air flowing into the combustion chamber.

8. A furnace having a heating chamber, a combustion chamber communicating with the heating chamber, a partition wall rising from the floor of the heating chamber and behind which wall the combustible gases from the producer flow upwardly to the combustion chamber, ports extending upwardly through the wall and through which heated air flows into the combustion chamber from a source of supply, and a passage intermediate between the top and bottom of said ports into which the air is received before passing into the combustion chamber.

9. In a furnace having a heating chamber wherein slabs and the like may be heated, doors in one side wall of the heating chamber through which the heated slabs may be removed from the latter, means for entering air and gas into the chamber through the same side wall, products-of-combustion outlet ports in the floor of said chamber beyond that side door which is most remote from the place where the air and gas are entered into the chamber, a recuperator below the chamber floor, the inlet to the recuperator facing on a passage which extends downwardly from said outlet ports whereby the products of combustion may enter the recuperator immediately on passing through said ports, means for supplying fresh air to the recuperator, an air-collecting chamber between said chamber floor and the top of the recuperator in which the air heated by the recuperator collects, passages connecting the air chamber with the means for entering the air into the heating chamber.

10. In a heating furnace adapted to permit

- objects to be disposed therein cross-wise of the direction of travel of the objects through the furnace, the method of heating said objects which comprises initially circulating hot gases lengthwise of the objects both above and beneath the same for a portion of their travel and thereafter to permitting the hot gases to flow in the direction of travel of the objects.
- 10 11. In a heating furnace adapted to permit objects to be disposed therein cross-wise of the direction of travel of the objects through the furnace, the method of heating said objects which comprises initially circulating hot gases lengthwise of the objects both above and beneath the same for a portion of their travel, and for the remaining portion of their travel causing the gases below the objects to divide into a plurality of independent streams for flow in the direction of travel of the objects.

In testimony whereof I affix my signature.

FORREST WILLIAM MANKER.
